UNITED STATES PATENT OFFICE

2,563,911

WIRES STRIPPER

Roland Dean Beck, Sycamore, Ill., assignor, by
mesne assignments, to Ideal Industries, Inc.,
Sycamore, Ill., a corporation of Delaware

Application November 19, 1945, Serial No. 629,485

7 Claims. (Cl. 81—9.51)

1

This invention relates to a wire stripper and has for one object to provide strong and powerful wire stripping means which can be used in stripping insulation from wires by a straight pull.

Another object is to provide an adjustable wire stripper suitable for stripping insulation from wires of several different diameters.

A still further object is to provide a so-called "bench type" wire stripper arranged preferably for permanent installation on a bench or other support.

Another object is to provide a wire stripper in which wire of different diameters may be dropped into an opening and in which gripping jaws are moved to engage the wire whatever its diameter.

Other objects will appear from time to time in the specification and claims.

The invention is illustrated more or less diagrammatically in the accompanying drawings, wherein:

Figure 1 is a top plan view of one form of the device.

Figure 2 is an end elevation with parts broken away.

Figure 3 is a bottom plan view of the device as shown in Figure 1.

Figure 4 is a fragmentary top plan view of a portion of Figure 1 showing the parts in a different position.

Figure 5 is a fragmentary bottom plan view based on the showing of Figure 3, but with the parts in a different position.

Figure 6 is a longitudinal vertical section taken at line 6—6 of Figure 2.

Figure 7 is a transverse vertical section taken at line 7—7 of Figure 1.

Figure 8 is a vertical sectional detail taken on an enlarged scale at line 8—8 of Figure 6.

Figure 9 is a side elevation of one form of stripping blade; and

Figure 10 is a section taken at line 10—10 of Figure 9.

Like parts are indicated by like characters throughout the specification and drawings.

As shown in the figures, the device comprises a base member designated generally by the numeral 1. This base member, as shown in the figures, comprises side parts which are not separately numbered and it may have portions 2 perforated as at 3 for attachment to a bench. The base 1 is preferably formed integrally and may be a casting or may be otherwise made. However it is made, it is formed with suitable parts or members to receive and support the various parts of the stripper assembly.

The base includes track-forming members 4, upon which a slide plate 5 is mounted to move. The plate is held in position on the tracks 4 by members 6 which may be removably held in place by screws 7, or otherwise. The slide plate is moved back and forth by a lever 8 which is

2

pivoted as at 9 upon one or more supporting members 10, which are attached to or form part of the base 1.

A spring 11 is attached to the lever 8 at one end as at 12, and at its other end it is attached to a portion 13 of the base as at 14. The lever may, if desired, be provided at its free end with a handle portion 15. The lever 8 in the particular form here shown is provided with an enlargement 16, which is provided in its upper surface with a slot 17, as shown particularly in Figure 6.

A stud 18 is fixed in the slide plate 5, and projects into the slot 17. It may, if desired, be positioned about the bushing 19 to reduce friction.

The slide plate is moved back and forth along the tracks 4 by movement of the lever 8, which may project through a slot 20, formed in one of the sides of the base 1. The spring 11 is biased to move the lever 8 to the extreme forward or inactive position as shown in Figure 1. Pivotally mounted on the slide plate 5 is a pair of jaw members 21, 21. These members are supported for rotation upon screws 22, 22 which are fixed in and preferably project through the slide plate 5. Each jaw member 21 is provided with an eccentrically curved and preferably roughened face 23.

The slide plate 5 is provided beneath each of the jaw members 21 with an arcuate slot 24. Through each of these slots projects a pin 25. As shown particularly in Figures 5 and 7, springs 26 are positioned one about the lower end of each of the screws 22. One end of each spring is secured to a pin 27 on the slide plate, and the opposite end of each spring is secured to one of the pins 25.

The springs 26 are biased to hold the pins 25 in the position shown in Figure 5, and thus to carry the jaws 21 toward the dotted line position of Figure 1, and thus to carry the jaws into engagement with each other if no wire is present, or to carry the jaws into engagement with a wire if one is present between them.

The pins 25 preferably have mounted toward their lower ends rollers or contact members 28 which are held in place by pins 29.

30 30 is a contact member or abutment mounted on the base 1, and arranged to contact the pins 25 or the rollers 28 when the slide plate 5 is moved to the extreme forward position. This condition is shown in Figure 3, and in that position, which corresponds to the position of Figure 4, the pins have been moved to the lower ends of the slots 24, and thus the jaws 21 have been rotated as far as possible away from each other.

The mechanism thus far described comprises the base, the slide plate, the means for moving it, the jaws on the slide plate, and the means for rotating them. The wire stripping blades and the

means for operating and controlling them will now be described.

31 is a portion of the base or a member attached to the base. Journaled in that member are two shafts 32, 32. These shafts are provided with slotted enlargements 33 adjacent the upper ends, screws 34, are positioned one in each of the enlargements 33. Blades 35 are removably and adjustably positioned in the slots of the enlargements 33 and are held in place by the screws 34.

As shown generally in Figure 1 and in detail in Figures 9 and 10 the stripping blades 35 are preferably beveled as at 36, and may be notched as at 37.

At their lower ends, each of the shafts 32 is slotted and is arranged to receive a set screw 38. Operating members 39 are positioned one in each of the shafts 32 and held in place by the set screws 38. These operating members are shown in Figures 3 and 8 particularly. They are arranged to be struck and moved by a contact member or abutment 40, which is carried on a piece 41 which is itself held to the slide plate 5 by screws 42. As shown in Figure 6 the piece 41 is cut away to provide clearance with respect to parts which it would otherwise contact.

When the slide plate is moved to the position of Figures 3 and 4 in which the jaws 21 have been rotated away from each other, the member 40 has struck the operating members 39 and rotated the shafts 32, thus moving the members 39 away from each other and correspondingly moving the stripping blades 35 away from each other. In this position the parts are ready to receive a wire.

Means may be provided for giving the shafts 32 a counter-rotation. As shown, this comprises a plunger 43 having an enlarged head 44 arranged to contact the operating members 39, as shown particularly in Figures 3 and 6. The plunger is mounted in a socket 45, fixed to the base portions 31 and is urged outwardly by a spring 46.

It is convenient to provide means for adjusting the length of the portion of insulation which is to be cut off. For this purpose, an adjustable stop is provided. As shown, this comprises a stop member 47 having an extended head 48 and a portion 49 shaped to fit upon a rod 50. This rod may be of any desired length and is set in the portion 31 of the base 1. A set screw 51 provides means for adjustably fixing the stop member at any point chosen on the length of the rod or supporting member 50.

If desired, a centering means may be provided for centering wires. This includes a notched or V-shaped member 52 which appears in plan in Figure 1, in section in Figure 6 and in dotted line in Figure 7. This member is secured to a shaft or pin 53 which fits within a socket portion 54 formed in the part 31 of the base 1. A set screw 55 is provided to secure it at adjusted height.

An insulated wire 56 is shown in the device and a section 57 of the insulation is shown as being severed.

The use and operation of this invention are as follows:

The device is secured or placed upon a suitable support which may conveniently be a work bench. When not in use, the spring 11 tends to move the lever 8 and with it the slide plate 5 to substantially the position indicated in Figure 3. In that position, the blades 35 are as shown in Figure 4.

When the device is to be used for stripping purposes, if the spring 11 has not moved the slide to the position of Figure 3, the handle 8 is moved toward that end of the base upon which the

blades are supported. The plate 5 is thus moved, either by the spring 11 or by the handle, from the position of Figure 1 toward the position of Figure 3, or as far as it can go in that direction. As this movement occurs, the member 40 contacts the operating members 39 and moves them and the shafts 32 to which they are fixed to the position shown in Figures 3 and 4. Thus the blades are moved apart to their maximum point of separation.

At the same time, the pins 25 are contacted by the member 30 and are moved to the bottom of the slots 24 into the position shown in Figures 3 and 4. Since the pins 25 are fixed one to each of the jaw members 21, this movement of the pins carries the jaws to the position shown in Figure 4. This is the position of maximum separation of the jaw faces and the apparatus is in position to receive a wire.

20 The wire is moved with its end against the stop face 48 and is laid between the blades 35 and the jaws 21 in the notch or center of the centering member 52. The lever 8 is now moved in the reverse direction away from that portion of base 25 which supports the blades.

As this occurs, the jaws 21 are moved by the springs 26 into contact with the wire which they grip as shown in the full line position of Figure 1. This movement of the jaws is caused by the springs 26 in the initial stage of movement of the slide plate 5. As the slide plate 5 moves away, the pins 25 are no longer held, by the part 30, in the inner ends of the grooves 24 and, hence, the springs 26 are free to move the jaws 35 into engagement with the wire 56. Movement of the slide plate in the same direction merely serves to cause the jaws 21 to grip the wire more firmly.

As this movement has been occurring the blades 35 are moved by the movement of the shafts 32 under the influence of the spring 46 and they are brought into contact with the wire and they sever the portion 57 of the insulation which lies between the blades and the stop 48. At the stage of the operation shown in Figure 1, this portion of insulation has been severed.

45 Further movement of the slide plate in the outward direction draws the severed portion of insulation clear of the wire and thus the operation of severing and stripping the insulation from the wire has been completed.

50 A reverse movement of the slide plate causes the operations above described to take place again in reverse order, and when the jaws have been brought again to the position of Figure 4 or to approximately that position, the wire is no longer gripped by them and may be removed.

55 The cycle of operations above described is carried out as often as it is necessary to strip insulation from a wire.

60 I claim:

1. In combination in a wire stripper, a base, a slide mounted to move therealong, a handle mounted on said base and engaging said slide, a spring connected to said base and to said handle, 65 and biased to move the slide and handle toward inactive position, a pair of cooperating wire gripping means pivoted on said slide, springs biased to move said means toward each other into wire gripping position, an abutment member on said base positioned when the slide is in one position to contact and to move said wire gripping means apart, and a pair of pivoted cooperating wire stripping blades pivotally mounted on said base, means biased to move said blades into stripping 70 position, a member on said slide positioned when 75

the slide is in said position to contact and to move said blades apart, said blade moving member and said gripping means abutment being so dimensioned that in the same position of the slide the wire gripping means and the blades are both separated for the reception of a wire to be stripped.

2. In combination in a wire stripper, a base, a slide mounted to move therealong, a handle pivotally mounted on said base and engaging said slide, a spring connected to said base and to said handle, and biased to move the slide and handle toward inactive position, a pair of cooperating wire gripping means pivoted on said slide, springs biased to move said means toward each other into wire gripping position, an abutment member on said base positioned when the slide is in one position to move said wire gripping means apart, and a pair of pivoted cooperating wire stripping blades pivotally mounted on said base, means biased to move said blades into stripping position, a member on said slide positioned when the slide is in said position to contact and to move said blades apart, said blade moving member and said gripping means abutment being so coordinated that in the same position of the slide the wire gripping means and the blades are both separated for the reception of a wire to be stripped.

3. In combination in a wire stripper, a base, a slide mounted to move therealong, a handle mounted on said base and movably engaging said slide, a spring connected to said base and to said handle, and biased to move the slide and handle toward a position of rest, a pair of cooperating wire gripping means pivoted on said slide, springs biased to move said means toward each other into wire gripping position, an abutment member on said base positioned when the slide is in one position to move said wire gripping means apart, and a pair of pivoted cooperating wire stripping blades pivotally mounted on said base, means biased to move said blades into stripping position, a member on said slide positioned when the slide is in said position to contact and to move said blades apart, said blade moving member and said gripping means abutment being so dimensioned that in the same position of the slide the wire gripping means and the blades are both separated for the reception of a wire to be stripped.

4. In combination in a wire stripper, a base, a slide mounted to move therealong, a handle pivotally mounted on said base and movably engaging said slide, a spring connected to said base and to said handle, and biased to move the slide and handle toward a position of rest, a pair of cooperating wire gripping means pivoted on said slide, springs biased to move said means toward each other into wire gripping position, an abutment member on said base positioned when the slide is in one position to move said wire gripping means apart, and a pair of pivoted cooperating wire stripping blades pivotally mounted on said base, means biased to move said blades into stripping position, a member on said slide positioned when the slide is in said position to contact and to move said blades apart, said blade moving member and said gripping means abutment being so dimensioned that in the same position of the slide the wire gripping means and the blades are both separated for the reception of a wire to be stripped.

5. In combination in a wire stripper, a base, a slide mounted to move therealong, a handle

pivotedly mounted on said base and movably engaging said slide, a spring connected to said base and to said handle, and biased to move the slide and handle toward a position of rest, a pair of cooperating wire gripping means pivoted on said slide, springs biased to move said means toward each other into wire gripping position, an abutment member on said base positioned when the slide is in one position to move said wire gripping means apart, and a pair of pivoted cooperating wire stripping blades pivotally mounted on said base, means biased to move said blades into stripping position, a member on said slide positioned when the slide is in said position to contact and to move said blades apart, said blade moving member and said gripping means abutment being so dimensioned that in the same position of the slide the wire gripping means and the blades are both separated for the reception of a wire to be stripped, said wire gripping means moving member and said blade moving member being effective only when the slide is in the position of rest.

6. In combination a wire stripper, a base, a pair of insulation-cutting blades carried from the said base, rotary supports for said blades pivoted on said base, a slide mounted for sliding movement with respect to said base, a pair of identically shaped wire gripping members mounted for rotation on said slide, said wire gripping members being provided with opposed faces eccentric to their points of rotation, spring means biased to urge said gripping members together, an abutment fixed on said base and positioned to contact parts of said gripping members and to move them in opposition to said springs, and an abutment member on said slide, positioned to contact the supports for said stripping blades and to move said blades apart.

7. In combination in a wire stripper, a base member, guides thereon, a slide mounted in said guides for sliding movement, a handle supported on said base, and means connecting said handle movably to said slide, a member biased to move said slide and handle in one direction, a pair of wire gripping members mounted on said slide for rotation, and means carried on said slide biased to move said gripping members toward each other for gripping, operating parts secured to said gripping members, an abutment fixed on said base and positioned to engage said operating parts, and in one position of the slide to move said gripping members apart, a pair of supporting members mounted for movement on said base, cooperating stripping members carried by said supporting members, means biased to move said supporting members to carry said stripping members into stripping position, a member carried by said slide and adapted in one position of said slide to contact and move said supporting members and thus to carry said stripping members apart.

ROLAND DEAN BECK.
